CLAIM

The ornamental design for a street clock, as shown and described.

DESCRIPTION

FIG. 1 is a perspective view of a street clock showing our new design;

FIG. 2 is a front view;

FIG. 3 is a rear view;

FIG. 4 is a bottom view;

FIG. 5 is a top view;

FIG. 6 is a right side view; and,

FIG. 7 is a left side view.

In FIG. 4, the broken lines defining the inside periphery of the street clock's outer structural wall, and the broken lines defining the outside periphery of the street clock's support post, represent boundaries, the area within which forms no part of the claimed design.

The cross-shaped features depicted by broken lines in FIG. 4 have been shown for the purpose of illustrating elements that form no part of the claimed design.
